(57) **CLAIM**

The ornamental design for a decorative container dome, as shown and described.

DESCRIPTION

FIG. 1 is a perspective view of a decorative container dome according to the present invention;

FIG. 2 is a side elevational view thereof;

FIG. 3 is a side elevational view thereof, rotated 90° clockwise from the side shown in FIG. 2; and,

FIG. 4 is a top plan view.

The broken line showing in FIGS. 1-4 is for illustrative purposes only and forms no part of the claimed design.
